UNITED STATES PATENT OFFICE.

WALTER D. ROSS, JR., OF ANNISTON, ALABAMA.

TWYER.

1,279,446.

Specification of Letters Patent. Patented Sept. 17, 1918.

Application filed January 16, 1918. Serial No. 212,034.

To all whom it may concern:

Be it known that I, WALTER D. Ross, Jr., a citizen of the United States, residing at Anniston, in the county of Calhoun and State of Alabama, have invented certain new and useful Improvements in Twyers, of which the following is a specification.

This invention relates to twyers and has special reference to twyers of the type disclosed in Letters Patent No. 1,205,568, granted to me November 21, 1916. One object of the present invention is to provide a construction whereby an increased volume of air will be admitted to the lower twyer and the blast issuing from said twyer thereby strengthened. A further object of the invention is to improve the construction and facilitate the removal of broken or burnt out parts.

20 The invention is illustrated in the accompanying drawings, in which—

Figure 1 is a vertical section of a cupola furnace having my improved twyers incorporated therein;

25 Fig. 2 is a horizontal section on the line 2—2 of Fig. 1;

Fig. 3 is a plan view of a portion of the lower twyer;

30 Fig. 4 is a detail perspective view of the parts of the lower twyer separated but in their proper relative positions;

Fig. 5 is a detail perspective view of the channel member which extends between the upper and lower twyers.

35 Fig. 6 is a detail perspective view of the filler blocks.

The cupola furnace 1 may be of the usual or any preferred construction and is equipped with the usual annular inclosing air box 2 connected through a conduit 3 with any convenient source of air under pressure. Upper and lower twyers are embedded in the wall of the furnace to admit air from the air box to the combustion chamber of the

45 furnace and direct the air currents onto the metal.

In carrying out my present invention, I employ at each lower twyer a lower twyer plate 4 which is substantially of the same construction as the lower twyer plate disclosed in my aforesaid patent, there being a division block 5 at its center and posts 6 at its ends, the inner walls of said posts converging outwardly and the posts and division

55 blocks being integral with the twyer plate or separate therefrom and rested thereon as

may be preferred. The upper twyer plate 7 rests at its ends upon the posts 6 and bridges the space between them, resting at its center upon the division block 5. This twyer plate 7 is equal in width to about half the width of the lower twyer plate and is of arcuate form, being of the same inside radius as the lower twyer plate and the furnace wall, and all the mentioned parts being built into the wall of the furnace as will be readily understood and as shown in Fig. 1 of the drawings. The upper twyer plate 7 is disposed over the inner portion of the lower twyer plate, and upon the outer portion of the lower twyer plate I place an air conducting and directing member 8 which rests at its ends upon the posts 6 and bridges the space between the said posts. This air conducting member is substantially an angle bar curved longitudinally to correspond to the arcuate form of the twyer plate and having a vertical flange 9 at its inner side which bears against the outer edge of the upper twyer plate 7. An upper horizontal flange 10 extends outwardly from the upper edge of the flange 9 and this flange 10 is constructed at its center with a notch 11 and at its ends with notches 12, while from the outer edge of said flange 10 at the ends thereof are depending flanges or feet 13 which are designed to bear upon the upper surfaces of the adjacent posts 6 and have their inner terminal edges meeting the inner vertical walls of the said posts. It will thus be readily seen that an open space is provided at the outer side of and above the lower twyer plate so that a greater volume of air may be admitted to the twyer than could be admitted by the space between the outer terminals of the posts. Filling blocks 14 are disposed upon the upper twyer plate 7 and have their outer ends bearing against the inner flange 9 of the air conveying member 8, while the upper surfaces of said blocks are flush with the upper surface of the flange 10, as clearly shown in Fig. 1. These several filling blocks are wedge-shaped and preferably are provided in two sizes which are arranged alternately. By providing a plurality of the blocks alternately of different sizes I am enabled to fit the blocks in place readily, and easily attain the desired uniformity of the inner surface of the furnace wall adjacent the blocks. As shown clearly in Fig. 1, the inner ends of these several filling blocks are projected beyond the inner

ends of the posts 6 and the twyer plates so that the furnace lining may be made thicker above the said blocks, and the under surface of the inner ends of the blocks are beveled, 5 as shown, so that the air blast may spread as it emerges from the tuyers. Resting upon the air directing member 8, and coinciding with the notches 11 and 12 therein, are air conveying channel members 15 which 10 are set into the outer surface of the furnace wall at intervals around the same and are provided near their upper ends with openings 16 around which on their inner surfaces are bosses 17. The upper tuyers or nozzles 15 18 are set in the furnace wall in an inclined position, as shown in Fig. 1, and have their upper ends beveled so that they will fit within the circular opening 16 and the bosses 17 and form a tight joint therewith. As the 20 upper tuyers or nozzles are inclined downwardly and inwardly, the air will be directed most efficiently upon the charge within the furnace.

It will be readily noted from the foregoing description taken in connection with the accompanying drawings, that the channel members 15 are disposed vertically and their upper ends are closed while their lower ends are open, said members consisting substantially of an inner plate 21, having outwardly extending flanges 22 at its side edges connected by a flange or web 23 at its upper end. The lower ends of the members rest upon the air directing members 8 around 35 the notches therein, and the space between the flanges 22 is open to the air box 2 so that the air entering the said box and filling the same will at once enter the channel members and pass therefrom into the interior of 40 the air-conveying members 8 and will be thereby crowded into the diverging passages through the lower tuyers while the air admitted to the upper ends of the channel members will pass through the nozzles or 45 upper tuyers 18. It will be readily noted that the ends of the air directing members 8 are disposed between the inlet openings of the lower twyer members inasmuch as they are supported by the posts at the ends of the 50 lower twyer members. The greater portion of the air admitted to the channel members, at the ends of the lower tuyers, will, conse-

quently, be caused to escape through the upper tuyers and this arrangement permits me to increase the number of upper tuyers, 55 as will be readily understood. I am, therefore, enabled to increase the volume of air directed upon the charge of ore without increasing the size or dimensions of the furnace and as a greater volume of air will be 60 permitted to pass through the tuyers the life of the parts exposed to the heat will be prolonged. The hollow construction of these parts also reduces the quantity of metal necessary and the provision of additional air passages and upper tuyers effects a more equal distribution of the air. The device is exceedingly simple in the construction and arrangement of its parts and may be applied to any furnace now in use at a 70 low cost. It very often happens, especially in large operations, that the upper twyer plate 7 will be burnt off and the filler blocks 14 be burnt out in sections. Sometimes, parts of the posts 6 are burnt off. 75 My construction permits the burnt member to be easily withdrawn and a new member substituted therefor without requiring an entire section to be torn out and rebuilt.

Having thus described the invention, 80 what is claimed as new is:

1. The combination of a lower twyer plate, posts at the ends thereof, an upper twyer plate supported by said posts and bridging the space between the same at the 85 inner side of the lower twyer plate, and an air-conveying member supported by said posts and bridging and communicating with the space between them at the outer side thereof. 90

2. The combination of a lower twyer plate, posts at the ends thereof, an upper twyer plate resting on said posts and bridging the inner portion of the passage between them, an air-conveying member resting on 95 said posts and bridging the outer portion of said passage and communicating therewith, and a vertically disposed air-conveying member resting at its lower end on and communicating with the interior of said 100 first-mentioned air-conveying member.

In testimony whereof I affix my signature.

WALTER D. ROSS, JR. [L.S.]
